UNITED STATES PATENT OFFICE.

THEODORE F. TAYLOR, OF BROOKLYN, NEW YORK.

CHEMICAL TELEGRAPH.

SPECIFICATION forming part of Letters Patent No. 289,173, dated November 27, 1883.

Application filed December 22, 1882. (No model.)

To all whom it may concern:

Be it known that I, THEODORE F. TAYLOR, a citizen of the United States, residing at Brooklyn, in the county of Kings and State 5 of New York, have invented new and useful Improvements in Chemical Telegraphs, of which the following is a specification.

My invention relates to that class of chemical telegraphs in which the transmission of signals is effected by an automatic transmitting apparatus in which a perforated non-conducting stip or fillet is employed to cause the proper "makes and breaks" of the circuit, the communication being recorded at the receiving 15 station by the electric decomposition of chemicals in a strip of chemically-prepared paper as the electric impulses pass through said paper, it being interposed in the circuit and gradually drawn along in contact with two 20 opposite terminals or electrodes; or the recording may be accomplished by the movements of a polarized relay of the Siemens or Hughes pattern, or any other suitable automatic recording-instrument.

25 The advantage of a successful use of automatic telegraphy is the capacity it gives one wire over the ordinary Morse. A successful use of automatic means anywhere from two hundred to two thousand words, against twenty-five to thirty by Morse and hand manipulation per minute. The great drawback to successful use of automatic has been "tailings," as it is technically called—that is, the message, instead of being received in clear, 30 well-defined marks, thus — —, is run together in one line, thus — —. Tailings are due to retardation of discharge of the lines—that is, it takes several times as long for a line 35 to discharge as it does to charge. To obviate

40 or remedy tailings retardation, many plans have been tried—the magnet in the shunt at the receiver by Edison, the "overflow-dam"—that is, a leak to ground through resistances—of Little, and many others which might be cited. It is also well known that the speed or rapidity of succession with which consecutive 45 signals can be sent over a telegraph-line is limited by the effects of electro-static induction, and therefore a rapid and reliable 50 means of clearing the line of its static charge has long been a great desideratum in tele-

graphic systems requiring rapidly-successive impulses—as in chemical telegraphy—and especially in systems of that class in which the recorder is required to produce a fac-simile of 55 the transmitted message. To remedy these defects in automatic systems, I have made use of the known law that the times of discharge of lines (other conditions being equal) vary as the square of the proportional lengths. 60 That is, given a line one thousand miles long and one second as the time of discharge of a momentary impulse, under same conditions if line be five hundred miles long the time of discharge will be only one quarter of a second. 65 Of course in these illustrations it is to be understood that the times are greatly exaggerated. Thus to work a long line automatically and economically I take advantage of the law, dividing the line physically or materially into 70 sections connected electrically, or, rather, for electrical action, by condensers. For example, a line two hundred miles long will require four times as long to discharge as a line of one hundred miles. Now, if we divide such a 75 line into two equal sections each short section will require but one-fourth the time the long line did in discharging—that is, the square root of four, which is two, divided by the number of sections, (two,) equal one, being 80 one-fourth of four, the time of the long line. A line three hundred miles long requires nine times as long to discharge as a line of one hundred miles, and if divided into three equal sections each section would require a time 85 proportionately equal to the square root of nine, which is three, divided by the number of sections, which is three, thus giving one—that is, one-ninth the time required for the long line. 90

It is a further object of my invention to reduce the time required for discharging a line by causing a reverse current to automatically succeed a recording-current, this being accomplished by utilizing for the purpose the reverse currents which result from the charge and discharge of the condensers which I use for connecting the short sections into which I divide a main line. 95

My invention consists in the combination, 100 with a telegraph-line conductor divided into two approximately-equal sections connected

for induction through a condenser, of an electric generator arranged to be connected to the terminal of one of the sections, a transmitter arranged to make and break the connection of the generator with said section, and a chemical receiver and recorder connected with the opposite line-terminal and ground, as will be hereinafter particularly described.

The accompanying drawing illustrates a chemical telegraph constructed according to my invention.

The letters L and L' indicate two approximately equal sections of a line-wire, having their adjacent ends connected, respectively, to the opposite sections of a condenser, C.

A is the automatic transmitting-instrument at a station at one end of the line, and B is the chemical receiving and recording apparatus at the other end. These transmitting and recording instruments are connected with the line, battery, and ground in the ordinary manner, and may be of any of the well-known types used in chemical telegraphy, and need not be particularly described. The condenser has a capacity equal to at least that of one of the sections of the line. A negative current does not mark the prepared paper of the recorder. If, therefore, the condenser C is charged with positive electricity from the battery E, as is done when the two electrodes of the transmitter come in contact through a perforation in the transmitting-fillet f, the condenser is charged with positive (+) electricity higher than that of the earth, and a positive (+) current charges one set of plates of the condenser, attracts a negative (—) charge to the opposite set of plates, and at the same time repels the positive (+) charge in the wire toward the receiving-station. In fact, the positive (+) charge in condenser separates the two electricities and sets up a pulsatory movement which marks the chemical paper at recording station

when it flows from the pen to earth, and clears that portion of the wire, but does not mark when the flow is from earth to the pen.

45

It will be observed that the pressure of the positive (+) charge on one section of the condenser results in the production of pulsations of positive (+) electricity alternately flowing down the receiving-pen, and then back to the wire, resulting from the cessation of the positive (+) tension of the condenser and the subsequent release of the induced negative (—) charge on the second set of plates of the condenser. I thus obviate the necessity of changing the pole-connections of the battery to line for the purpose of sending a reverse current to clear the line of a static charge.

50

55

I am quite well aware that condensers have been interposed in electric circuits, and also that condensers have been connected with the opposite terminals of telegraph-lines, and I do not claim, broadly, such applications of condensers.

Having thus described my invention, what I claim is—

The combination, with a telegraph-line conductor divided into two approximately equal sections connected for induction through a condenser, of an electric generator arranged to be connected to one terminal of one of said sections, a transmitter arranged to make and break the connection of the generator with the said section, and a chemical receiver and recorder connected with the opposite line-terminal and ground, substantially as described.

70

75

In testimony whereof I have hereunto set my hand and seal in the presence of two subscribing witnesses.
